Inventor:

Gustaf A. Carlson
By his attorney, Lee, Crittenden & Miles,
Attest,

UNITED STATES PATENT OFFICE.

GUSTAF A. CARLSON, OF CHICAGO, ILLINOIS, ASSIGNOR TO THE BOYE NEEDLE COMPANY, OF CHICAGO, ILLINOIS, A CORPORATION OF ILLINOIS.

CURTAIN ROD.

Application filed March 5, 1923. Serial No. 622,868.

To all whom it may concern:

Be it known that I, GUSTAF A. CARLSON, a citizen of the United States, residing at Chicago, in the county of Cook and State 5 of Illinois, have invented new and useful Improvements in Curtain Rods, of which the following is a specification.

The present invention relates to curtain-rods adapted to be applied either to a 10 window-frame or to a sash; and the primary object is to provide a very simple and cheap curtain-rod which is well adapted to its purpose and which can be applied to a window-frame or sash-frame with great facility.

15 The invention is illustrated in its preferred embodiment in the accompanying drawing, in which—

Fig. 1 represents a broken plan sectional view of a window-frame with the improved 20 curtain-rod applied thereto, the curtain-rod being shown brokenly; Fig. 2, a broken horizontal sectional view showing the attachment with the frame made in a slightly different manner; Fig. 3, a similar section 25 showing the curtain-rod attached to the frame within the opening of the frame; Fig. 4, a broken sectional view taken as indicated at line 4 of Fig. 2; Fig. 5, an enlarged broken sectional view illustrating 30 the manner in which the wire-rod end-sections are connected with the intermediate coiled wire section; Fig. 6, a broken perspective view showing the hooked outer extremity of one of the wire-rod sections; 35 and Fig. 7, a view partly in section, showing the shank of the wire-rod section lengthened to provide for greater adjustment.

In the construction illustrated, A represents 40 a window-frame; and B represents the improved curtain-rod applied thereto.

The curtain-rod B comprises an intermediate coiled wire section 1, a pair of wire-rod end-sections 2 adjustably connected with 45 the section 1, and clamping sleeves 3 which serve to secure the members 2 to the member 1.

The end-sections 2 are provided with means for attaching them to a frame, such

as a window-frame or sash-frame. In the 50 form illustrated, each member 2 has its outer end provided with a hook 2^a. The member 2 is also provided with a shank 2^b, which extends into the end-portion of the coiled wire section 1 and is provided within 55 the coiled member with a crimp or bend 2^c. The sleeve 3 is adapted to slip over the coiled wire member and clamp the coiled member upon the crimped portion of the shank. Because of the cramped engagement, any stretching force exerted will cause the members to be gripped together 60 the more tightly. However, it is possible to force the sleeve away from the gripping position, so that the shank can be adjusted 65 within the coiled member.

It will be understood that by reason of the great resiliency of the coiled wire member, the member may be stretched a considerable distance so as to span an opening 70 greater than the length of the curtain-rod. If the curtain-rod is to be applied to an opening of less width, the end-portions of the coiled wire member may be cut off as much as may be necessary.

75 A slight modification providing for greater adjustment without the necessity of cutting off the ends of the coiled wire member is shown in Fig. 7. In this case, the wire-rod member is designated 2^d. The shank of the member is considerably lengthened; otherwise, the construction is the same as already described, and the parts are similarly lettered.

80 The curtain-rod may be applied to the window-frame by engaging the facing strips 4, the hooks engaging the remote edges of said strips; or the hooks may be connected with screw-eyes 5, attached to the frame either in the manner shown in Fig. 2 85 or the manner shown in Fig. 3.

90 The improved device is extremely simple, may be manufactured cheaply, and may be applied with great facility. The improved device renders unnecessary the use of 95 brackets for attaching the rod to the window-frame or sash-frame.

The foregoing detailed description has

been given for clearness of understanding, and no unnecessary limitations should be understood therefrom.

What I regard as new and desire to secure by Letters Patent, is:

A curtain-rod comprising a coiled wire section, a wire-rod section having one end provided with means for attachment to a

frame and having the other end crimped and extending into the coiled wire section, and a sleeve embracing the coiled wire section at the portion thereof which embraces the crimped end portion of the wire rod and clamping said sections together.

GUSTAF A. CARLSON.
